UNITED STATES PATENT OFFICE.

ENOCH SHADLE, OF McCRRORY, ARKANSAS.

BOLL-WEEVIL MACHINE.

Application filed January 2, 1923. Serial No. 610,135.

To all whom it may concern:

Be it known that I, ENOCH SHADLE, a citizen of the United States, residing at McCrory, in the county of Woodruff and 5 State of Arkansas, have invented certain new and useful Improvements in Boll-Weevil Machines, of which the following is a specification.

My invention relates to improvements in 10 boll weevil collectors, and the primary object thereof, resides in the provision of such a device that is comparatively simple of construction, inexpensive of manufacture, and highly efficient in operation.

15 With these general objects in view and others that will appear as the nature of the invention is better understood, the same consists in the novel construction, combination, and arrangement of parts herein- 20 after more fully described, illustrated in the accompanying drawings, and pointed out in the appended claims.

In the drawings forming a part of this application, like numerals of reference indicate similar parts in the several views, and 25 wherein:

Figure 1— is a side elevational view of the device constructed in accordance with the present invention.

30 Figure 2— is a top plan view thereof.

Figure 3— is a vertical longitudinal cross sectional view of the device.

Figure 4— is a transverse cross sectional view taken substantially upon the line 4—4 35 of Figure 2.

Figure 5 is an enlarged vertical sectional view of the weevil receiving receptacle on the line 5—5 of Figure 3, and;

Figure 6— is an enlarged transverse cross 40 sectional view of the receptacle, and taken substantially upon the line 6—6 of Figure 3.

With reference to the drawings, my device includes the provision of a frame embodying spaced longitudinally disposed side 45 members 1 and 2, integrally joined at their rear ends by a transverse connecting bar 3. The forward end of the side bars 1 and 2 constituting the frame are bent upwardly as more clearly shown in Figures 1, 2 and 50 3, and are integrally joined by a connecting bar 4.

Engaging over the frame bars 1 and 2, and substantially intermediate the ends thereof, is an arched wheel supporting axle 55 5. The opposite ends of this arched axle 5

are rounded for loosely receiving thereon supporting wheels 6.

Engaging over the rounded ends of this axle, and inwardly of each supporting wheel 6, are a forwardly extending longitudinal arms or bars 7, these arms or bars being formed with collars 8, at their inner ends for this purpose. The opposite outer ends of each member 7 is secured as at 9 to the lower ends 10 of an inverted substantially 60 U-shaped bracket 11, the side legs of this bracket engaging over the bars 1 and 2 of the frame, and adapted to be secured thereto as at 12. The inner end of a thill pole 13^a extends beneath the front connecting member 4 of the side frame bars 1 and 2, and also beneath the said inverted U-shaped bracket 11, to be secured to these members as at 13 and 14 respectively. This thill pole 13^a may be provided with any desirable 65 form of animal draft appliance 15.

Supported between the longitudinal bars 1 and 2 of the frame by brackets 16, carried by the side bars of the frame, is a receptacle 17, having a detachable cover 18. The front wall of this receptacle 17 is provided with an opening 19, for receiving one end of a suction pipe 20, the other end of this suction pipe having communication with a fan casing 21, within which is a suitable suction 70 fan, (not shown).

This fan, together with the suction pipe 20 is supported by a vertically disposed bracket 22, secured to the adjacent frame bar 2, and the shaft 23 of the fan within the casing 21 has a relatively small sprocket gear 24 secured thereto.

The adjacent one of the supporting wheels 6 of the machine is formed with an inwardly extending hub portion 25 engaging over the rounded end of an arched axle 5, and having formed thereon, a relatively large sprocket gear 26. Trained over the said gear 24 upon the fan shaft 23, and the larger 26, 90 is a sprocket chain 27 for consequently rotating the fan within the casing, when the machine is moved over the ground, for creating a suction within the receptacle 17, and through the suction pipe 20, the fan casing 21 having an outlet opening 28 therein. 100 Substantially centrally within the receptacle 17, there is formed a centrally sloping wall 29. The central portion of this wall 29 is transversely curved, so as to provide a casing 30, for the reception of 105 110

a rotating device 31. This casing being provided with an opening 32 at the front side thereof. As more clearly shown in Figures 3 and 6, this rotary device is in the form of a transversely extending cruciform member having a long and short pintle 32 and 33 respectively, engaging within openings at the opposite side walls of the receptacle 17. The long pintle 32 has 10 keyed thereto a sprocket gear 34, and this pintle is further supported by an arm member formed upon the said bracket 22. The before mentioned sprocket chain 27 is also trained over this latter mentioned sprocket 34 for consequently rotating the said device 31, when the machine is moved over the ground.

Arranged within the receptacle 17, and between the sloped wall 29 and cover 18, is 20 an inclined wire mesh partition screen 35, and rearwardly of this partition screen and at opposite sides of the receptacle 17, are the outlet ends of a pair of inlet nozzles 36, communication being established between 25 these nozzles and the interior of the receptacle by suitable openings formed in the rear wall thereof. These nozzles 36 are adapted to extend over the opposite sides of the machine frame, and to have their inlet ends slightly above the ground as shown 30 more clearly in Figures 1, 3 and 4, any desirable support 37 being provided between the nozzles and the machine frame.

Beneath the partition wall 29 within the 35 receptacle 17, the rear wall of this receptacle is provided with an opening for permitting of the entrance of a sliding drawer 38 thereinto, and in view of the above description, it will at once be apparent that 40 when my improved boll weevil collecting machine is moved over the ground, the suction fan within the casing 21 will be actuated through the instrumentality of a sprocket chain connecting 27, which chain 45 will consequently establish a suction through the nozzles 36, into the casing 17 through the exhaust pipe 20, and thence through the outlet opening 29 in the said fan casing 21. Together with the rotation 50 of the suction fan, the device 31 will be rotated in the direction of the arrows shown in Figure 3, which rotation is also occasioned by the chain connection 27 trained over the sprocket gear 34, upon the end pintle 32 of this valve, and in view of the 55 screen 19 between the inlet end of the pipe

20 and the outlet ends of the nozzles 36, the boll weevils and punctured squares drawn up by these nozzles will strike against this screen and be prevented from entering the 60 said exhaust pipe 20. In view of the opening 32 within the casing 30 formed within the partition wall 29, the weevils and punctured squares will be suitably conveyed by the device 31 into the drawer 38 to be removed whenever desired. It will at once be apparent that in view of the specific construction of the casing 30 formed within the partition wall 29, any liability of the 65 weevils or punctured squares to gain access to the upper portion of the receptacle 17 will be prevented. In other words the device 31 serves additionally as a non-return device to prevent retrograde movement of weevils or punctured squares to a point 70 above the partition 29. Consequently there is no liability of the chamber above the partition and back of the screen 35 being choked with weevils and punctured squares.

The machine frame has disposed upon the 80 rear end thereof, any desirable form of spring seat 39, and while I have herein shown and described the preferred embodiment of the present invention, it is nevertheless to be understood that minor changes 85 may be made therein, without departing from the spirit and scope of the invention as claimed.

What I claim as new is:—

A boll weevil collecting and destroying 90 machine comprising a wheel mounted frame, a receptacle mounted upon the frame, collecting nozzles connected with upper portion of the receptacle, means for exhausting air from the receptacle and located at the side thereof opposite the side at which the nozzles communicate with the receptacle, an inclined screen located within the receptacle and disposed between the collecting nozzle and the air exhausting 95 means, a trough located in the lower portion of the receptacle and having synclined side sections and provided between the said side sections with a semi-cylindrical foraminous section, a rotary member journaled above the cylindrical section of the bottom of the trough and having blades adapted to engage the upper surface of the trough and means for rotating said rotary element. 100

In testimony whereof I affix my signature.
ENOCH SHADLE. 110
